UNITED STATES PATENT OFFICE.

HAROLD P. BROWN, OF CHICAGO, ILLINOIS.

SYSTEM OF ELECTRIC LIGHTING.

SPECIFICATION forming part of Letters Patent No. 330,465, dated November 17, 1885.

Application filed June 8, 1885. Serial No. 167,952. (No model.)

To all whom it may concern:

Be it known that I, HAROLD P. BROWN, a citizen of the United States, residing at Chicago, in the county of Cook and State of Illinois, have invented a new and useful Improvement 5 in Electric Lighting, of which the following is a specification.

This invention relates to the art of operating groups of incandescent lamps from an 10 arc-light or high-tension circuit by means of an automatically-variable resistance-shunt around each group of incandescent lamps; and it relates more particularly to certain improvements in the apparatus or mechanism 15 for automatically varying and controlling the resistance of the shunt-circuit.

In the accompanying drawings, which form a part of this specification, and in which similar letters of reference indicate like parts, 20 Figure 1 is a front elevation of a device embodying my invention. Fig. 2 is a section on line 2 2 of Fig. 1. Figs. 3 and 4 are vertical sections on lines 3 3 and 4 4 of Fig. 1. Fig. 5 is a detail side elevation of the grooved 25 slide attached to the movable core of the solenoid, and by means of which the contact-pieces that vary the resistance of the shunt are moved in and out of the mercury-contact. Fig. 6 is a central longitudinal section of the 30 dash-pot. Figs. 7, 8, 9, and 10 are detail views of parts, hereinafter to be explained; and Fig. 11 is a diagram view showing the arrangement of circuits. Fig. 12 shows a modification.

35 In said drawings, A represents the main or arc light circuit; B, the local or incandescent lamp circuit, in which are included, on suitable branch wires, b, the incandescent lamps b' in multiple arc; and C is the shunt-circuit around the group of incandescent lamps, and 40 in which is included the variable resistance c.

As shown in the diagram view, the shunt and lamp circuits diverge at a point, as x, and reunite at a point, as x'.

45 D is an electro-magnet or relay having a fine-wire or high-resistance coil, D', which is included in the lamp-circuit on a branch wire, b, like one of the lamps. This relay has two armatures, d and d', attached to the two switch-levers d² and d³, respectively, the function of 50 which is to open and close the two short circuits E and F around the two coils E' and F'

of the double solenoid G. The coils E' and F' are both included in the main circuit; but they both remain normally short-circuited. 55 The short circuit E diverges from the main circuit at a point, as x², and reunites at x³, and the short circuit F leads from a point, as x⁴, and reunites at a point, as x⁵. When, by reason of the extinguishment of one or more 60 lamps in the group, or other cause, too great a portion of the current is passing through the lamp-circuit, the armature d will be attracted by the magnet D, thus moving the switch-lever d² and opening the short circuit 65 F, so that the main current will be forced to pass through the coil F' of the solenoid, and thereby pull its movable core G' to the left, and thus diminish the resistance of the shunt-circuit until only the proper amount of current 70 will pass through the lamp-circuit, the function of the solenoid G being to operate the contact maker or mechanism which changes the resistance of the shunt; and when, on the other hand, the current on the lamp- 75 circuit falls below its proper amount, the short circuit E is in like manner broken, and the current forced to pass through the coil E', thereby pulling the movable core G' to the left and increasing the resistance of the shunt 80 until the current again properly divides between the lamp and shunt circuits, when the armature d of the relay D will again assume its normal position, thus re-establishing the short circuit E and cutting out the coil E'. 85

The general arrangement of circuits which I have above briefly described constitutes the subject-matter of a previous application filed by me under date of December 19, 1884, and numbered 150,737, and the same is therefore 90 not herein claimed.

The present improvement consists, in connection with such or an equivalent system of circuits, in the combination, with the movable core or armature of the solenoid or electro-motive device for operating the resistance-changing mechanism, of a dash-pot or other equivalent device to prevent sudden or irregular movements of said core and the consequent excessive and irregular changes in the 95 resistance of the shunt.

It also consists, in connection with a series of movable contacts connected with different parts of the variable resistance, of a mercury-

contact covered with glycerine or some hydrocarbon to diminish as much as possible the friction in making and breaking the connections, and at the same time secure a perfect 5 contact and prevent sparking as the connections are made or broken.

It also consists in employing a grooved slide or cam attached to the movable core of the solenoid for moving the contact-pieces in and 10 out of the mercury.

It also consists in the peculiar construction 15 of these contact-pieces and their arrangement or combination with said slide, whereby the friction of said contact-pieces against the slide is maintained the same whether the contact-pieces are pressed into the mercury or raised out of it, or part in and part out.

It also consists in combining with the relay-armature levers a weighted line for retracting 20 the same, instead of the usual spring, in order to prevent failure or inaccuracy in the operation of the apparatus, owing to the springs getting out of adjustment by changes in temperature or other causes.

25 It also consists in the novel devices and combinations of devices hereinafter more particularly pointed out in the claims.

H represents the frame or case, preferably made of cast-iron, in or upon which the various parts are mounted. The double solenoid G is secured to this frame at each end by suitable screws, h.

K is the mercury vessel or trough, extending 35 between the two spools of the solenoid, and provided at each end with flanges k, by which it is screwed to the inside spool-heads of the solenoid. This trough is preferably made of cast-iron, and it is partially filled with mercury k', which is covered with glycerine k².

40 L is the grooved slide or cam, by means of which the movable contact-pieces N are made to make and break connection with the mercury in the vessel K. This slide is rigidly attached to and carried by an arm, L', which 45 is securely bolted to the sliding core G' of the solenoid, so that the slide will be carried back and forth with said core. The upwardly-bent end l of the arm L' carries on a suitable pin or trunnion, l', a friction-wheel, l², which travels 50 back and forth on the tracks or flanges l³ on the outer face of the mercury-trough K. The movable contact-pieces N preferably consist of wires inserted through suitable holes in the insulation block or plate N', by which they are 55 supported. The wires N all extend in the same plane, and they are bent or folded near their outer ends to form the knees or projections n, which fit in the groove l³ of the slide L. The extreme ends n' of the wires N are again bent to 60 project downward into the mercury-cup. The contact-pieces N should be made of spring-wire, and they should be flattened or thinned near the block N', as shown at n², so that they may be easily depressed into or raised out of 65 the mercury by movement of the grooved slide L. The slide L should be so arranged in relation to the wires N that its middle line

will lie in the same plane as the wires N, so that each of said wires, when depressed into the mercury, will press against the upper wall 70 of the groove l³ with the same force as it presses against the lower wall of said groove when it is raised out of the mercury. In this way the degree of friction of the contact-pieces N on the grooved slide is rendered almost constant whatever the position of the slide. The length of the slide L is about twice the space occupied by the series of contact-pieces N, so that all of said contacts may be either raised or depressed at once if necessary. 80

It is preferable that the contact-pieces N consist of flat carbon blocks c', contained in the pans c², lined with the insulating plates or strips c³, which may preferably be of slate, metal plates c⁴ being inserted at suitable intervals between 85 the carbon blocks, with which metal plates the contact-pieces N are connected. It is obvious that when all the contact-pieces N except the right hand one are raised out of the mercury, the shunt-circuit current will be 90

forced to pass through the whole of the resistance c; but when the slide L is moved to the left and all the contact-pieces N are in connection with the mercury, the shunt-circuit current will take the left-hand wire N 95 and therefore only pass through a small portion of the resistance c. When the resistance of the shunt-circuit is slight, it will be understood that the greater portion of the main current will pass through the shunt, and to 100 prevent the resistance from being too much heated I make the carbon blocks c' in the first part of the series of about twice the area of those in the subsequent or latter part, and for this reason also I place the first carbon-pan above the others, so that the heat from 105 the former will not be communicated to the latter. The carbon blocks in the lower pans do not need to be so large as in the upper one, because when the current passes through the lower pile it is then only a small fraction of the total or main current, owing to the greater resistance in the shunt. By this disposition of the carbon blocks I am enabled to make a considerable saving in the aggregate amount of material required. The pans 110 c², which contain the carbon blocks, are best made of thin sheet-iron, and they may be conveniently supported on shelves or projections 115 h³, secured to or cast upon the box H. 120

M is the dash-pot pivoted at its lower end to a bracket, h', on the frame, and having its piston-rod M' pivoted to the arm L', which is secured to the movable core of the solenoid. The piston-rod has a threaded end, m, by 125 which it is secured to the piston m', and the duct m² communicates with the threaded hole in the piston, so that by screwing the piston-stem in or out the size of the duct may be varied and the motion of the solenoid-core G' thus adjusted and regulated as may be desired. As the piston is round and fits easily in the dash-pot, in order to hold it from turning 130 when the piston-stem is to be screwed in or

out, I provide a little pin or lug, m^3 , on the piston, which engages in a corresponding cavity, m^4 , in the head of the dash-pot. To make this adjustment it will be understood that the 5 piston-stem is to be first uncoupled from the arm L' .

In lieu of the dash-pot other equivalent or substitute motion-regulating devices may be used in this combination, with the core of the 10 solenoid and the contact making and breaking device operated thereby. The switch-levers d^2 d^3 , operated by the relay-magnet D, are both bent levers, and their horizontal arms are each provided with vertically-adjustable 15 contact-pieces or screws d^4 d^5 , which make connection with the mercury in the cups d^6 d^7 . The switch-levers d^2 d^3 , in order to prevent friction, are connected by their flat flexible springs d^8 d^9 with the base-block d^{10} , which is 20 preferably of wood. The switch or armature levers d^2 d^3 are retracted by means of weighted lines d^{11} d^{12} , which are connected at one end to said levers and at the other to eyes or hooks d^{13} d^{14} on the frame. The weights for these lines 25 are preferably made in two screw-threaded or extensible parts, d^{15} d^{16} , so that by screwing or unscrewing said parts the line may be shortened or lengthened and its retracting force thus adjusted.

30 In order to guard against injury to the apparatus and lamps, I include in the circuit an electro-magnet, O, having a pivoted armature-lever, o, provided with a catch, o', the function of which is to hold up the contact-piece 35 P and break the short circuit P' whenever the lamps are in use, and to release said contact-piece and close said short circuit whenever the current through the coil of the magnet O ceases. The lever o will swing back by its 40 own gravity when the current through the magnet O ceases, as it is pivoted to one side of its central line. When the current is again turned on or starts up, it is obvious that both the lamps and the resistance in the shunt will 45 be cut out or short-circuited until the contact-piece P is again raised out of the mercury. This of course could be done in various ways—as, for example, by connecting the switch P with the armature of the magnet O, or by connecting it with the switch by which the group or building is connected with the main circuit; but it is desirable that the resistance-changing 50 mechanism should be put through its movement before the short circuit P' is broken and the current reaches the lamps, in order that the resistance of the shunt may be first reduced to its minimum or to a small amount, so that if only one or two lamps should at the instant happen to be turned on no injury would 55 result, and so that also the resistance-changing mechanism may be, so to speak, tested and found capable of performing its work before the current reaches the lamps. For these 60 reasons I operate the switch or contact piece P by means of a groove or cam, p, on the slide L, the incline or rise of said cam being located 65 near the right-hand end of the slide, so that

it will not operate to raise said contact-piece P out of the mercury until said slide reaches the extreme limit of its throw to the left, and 70 the resistance of the shunt thus reduced to its minimum. The relay-magnet D is provided with a coarse-wire or low-resistance coil, D², which is included in the short circuit P', so 75 that the current on this short circuit will energize the magnet D and pull the armature or switch lever d^2 and break the short circuit F, and thus cause the current to flow through the left-hand coil, F', of the double solenoid and pull the slide L to the left, as before described. 80 The moment this is done the contact-piece P will be raised out of the mercury and the short circuit P' broken, when the current will then pass through the shunt and lamp circuits. As 85 the resistance of the shunt is at its minimum at this moment of beginning, if two or more lamps happen to be turned on in the group the slide L will almost instantly begin to move to the right, and continue so to do until the resistance of the shunt is so increased as to 90 properly divide the current between the lamps and shunt.

To guard against injury to the lamps or apparatus in case the core G' of the double solenoid should stick or for any cause the apparatus 95 should fail to perform its functions, I provide means for cutting out or short-circuiting the lamps whenever the current on the lamp-circuit and through the fine-wire coil D' of the relay D may happen to increase to a certain 100 prescribed limit above its normal or proper amount. This may be conveniently done by providing the relay D with a secondary armature-lever, R, pivoted to a bracket or post, h², 105 secured to the frame, and which, when attracted by an increase of current in the magnet, operates to swing or pull the catch o' to one side and allow the contact-piece P to drop into the mercury, and thus close the short-circuit P'. The armature-lever R is provided with a threaded arm, r, and adjustable weight r', by means of which said armature-lever is retracted and so held until the current on the coil D' of the magnet D for some cause reaches a certain fixed extent above its proper amount. Ordinarily the 110 armature-lever R should be so adjusted as not to be pulled up or operated until two or three lamps in the group have been extinguished without causing any change in the resistance of the shunt through some failure of the apparatus to perform its functions properly. R² is 115 an extension of the core of the relay D, preferably consisting of a soft-iron screw for convenience of operating the armature-lever R. The catch o' is made thin at o², so that it may spring 120 to one side under action of the armature-lever R, and the contact-piece P is provided with a shoulder or projection, p², which rests upon the catch o'. To prevent the contact-piece P moving laterally under action of the lever R, I extend the head o³ of the magnet O down, and 125 provide it with a slot, o⁴, in which the contact P can move up and down, but not laterally. 130

In Fig. 12 I have shown what I deem a better

and more improved form of device for releasing the contact-piece P when the current through the fine-wire coil D' of the magnet D becomes too strong through failure of the mechanism to 5 operate properly or other cause. This improved device consists simply in mounting the stop or jam-nut and screw d⁷, which limits the movement of the armature-lever d² upon the end of the lever R, so that the increased pull of 10 the magnet D on the lever d² will operate the lever R, and, further, in providing the lever R with a contact-piece, r², which, when said lever R is raised, closes a short circuit, Q, between the two spring-contacts q q', thus cutting out 15 the coil of the magnet O, so that its armature-lever o will drop away, and thus release the contact-piece P.

Q' represents a block of fiber or other insulation, upon which the lever R and the contact-pieces q q' are secured. It will of course 20 be understood that the different parts are properly insulated from each other where necessary. As this is well understood by those skilled in the art, I have not thought it necessary 25 nor endeavored to point out with particularity the insulating material. Some parts, such as the slide L, the blocks which support the wires N, &c., are most conveniently made of insulating material, like gelatinized fiber, for example. The spools or frame 30 G of the double solenoid may of course be formed of insulating material; but I find that, owing to the heat and other causes, more satisfactory results are produced by making them 35 of cast brass or metal, in which case, of course, these should be insulated from the frame H by rubber bushings and washers around the screws h, and also from the metal mercury-vessel K.

40 As shown in Fig. 11, the main circuit A leads from the right-hand binding-post to the helix E' of the double solenoid, thence from the point x³ along the wire A to the other coil, F', of the double solenoid, and thence from the 45 point x⁵ along the wire A, through the low-resistance coil of the magnet O to the point x, where the lamp-circuit B and the variable-resistance shunt C diverge. The lamp-circuit B leads from the point x to the left-hand binding-post B', thence along the several branch wires b, through the lamps b' to the right-hand wire B and binding-post B', and thence along the 50 wire B to the mercury-trough K, where it reunites, as at x', with the shunt-circuit C. 55 One of the branch wires b leads from the left-hand binding-post B', through the inner or fine-wire coil D' of the relay-magnet D to the right-hand binding-post B'. The variable-resistance shunt C extends from the point x 60 through a greater or less portion of the resistance c, and thence through one of the movable contact-pieces N to the mercury in the mercury-cup, where the shunt-circuit reunites with the lamp-circuit, and the reunited circuit 65 then passes to the left-hand binding-post, A', along the main wire. The short circuit E, which cuts out the right-hand coil, E', of the

double solenoid, leads from a point, as x², to the mercury-cup d⁶, thence through movable contact-piece or switch-lever d² and wire 70 E back to the main circuit at a point, as x³. The short circuit F leads from a point, as x⁴, on the main circuit to switch-lever d³, thence to mercury-cup d⁷, and back to the main circuit at a point, as x⁵. The short circuit P', which 75 serves to cut out both the lamps and the variable resistance in case of a failure of the apparatus to act, extends from a point, as x⁶, on the relay branch wire b, through the coarse-wire or low-resistance coil D² of the relay-magnet D, and thence through the movable contact-piece P to the mercury-cup K and the main circuit A.

A' A' represent the main-circuit binding-posts, and B' B' the local binding-posts. The 85 levers d² and d³ form part of the short circuits E and F. Equivalent devices may of course be used for the dash-pot in its combination with the movable core of the solenoid to regulate the motion thereof. I should, perhaps, 90 also state that my experiments and experience have shown that fly-wheel mechanism does not produce very satisfactory results, owing to the inertia making the resistance-changing mechanism too slow to start and difficult to 95 stop at the right point, and that friction-brake mechanism I have found difficult to keep uniform in its action, and specially liable to stick and cause the core of the solenoid to start very hard. The dash-pot, I have found, produces 100 the best results; but I of course do not limit myself thereto, as other equivalent or substitute devices may be used in its place in the combination. I have also discovered that in the use of the mercury contact with the 105 movable contact pieces or wires N, if the contact piece or wire N has a square end, when it is being withdrawn from the mercury a globule of mercury will follow up the wire, or, rather, form on its end above the surface 110 of the mercury, thus producing irregularity in the making and breaking of the connections. To prevent this I provide the contact-pieces N, P, d⁴, and d⁵ with pointed or sharp ends. By this means I am enabled to withdraw the 115 contact-pieces from the mercury without causing any drop or portion of the mercury to rise above the surface thereof, and thus continue the electrical connection after it should be broken.

120 It will be observed that in the drawings, Fig. 11, I have only indicated three lamps of the group. The apparatus shown is specially designed for operating twelve lamps in the group. It may, however, operate any number 125 of lamps up to twenty-four by making some slight changes in the relative position of the metal plates c⁴ in the resistance c. It is preferable, however, to have about twice as many divisions in the variable resistance as there are 130 lamps in the group, so as to have means of compensating for variations in the resistance of the carbon blocks due to changes in the temperature. The carbon pile or blocks may

preferably be made of the pulverized residue from the distillation of coal. They are commonly known on the market as "carbon battery-plates."

5 I claim—

1. The combination, with a main circuit, of a local or incandescent lamp circuit having included therein on suitable branch wires a number of incandescent lamps in multiple arc, a shunt around said lamps having therein a variable resistance, a relay, an electro-motive device set in operation by said relay for varying the resistance of said shunt, and a dash-pot for regulating the movement of said electro-motive device, substantially as specified.

2. The combination of a main circuit with a lamp - circuit having included therein a number of incandescent lamps in multiple arc, a variable-resistance shunt around said lamps, a double solenoid having a sliding core for varying the resistance of said shunt, a dash-pot for regulating the movement of said core, and a relay to control the circuit through one 25 or the other coil of said solenoid, as may be required, substantially as specified.

3. The combination, with a group or number of incandescent lamps in multiple arc, of a shunt around such group of lamps, a variable resistance in said shunt, a series of movable contact-pieces connected with different parts of said resistance, a mercury-contact, and an electro-motive device for moving said contact-pieces in and out of the mercury to 35 vary said resistance, substantially as specified.

4. The combination, with a variable-resistance shunt around a group of incandescent lamps, of a mercury-contact, a series of movable contacts leading to different parts of said 40 variable resistance, and a slide having a cam or groove for moving said movable contacts in and out of the mercury, substantially as specified.

5. The combination of a variable-resistance shunt around a group of incandescent lamps with a mercury-contact, a series of movable contact-pieces, a slide having a cam or groove, and an electro-motive device for operating said slide, substantially as specified.

5c 6. The combination of a variable-resistance shunt around a group of incandescent lamps with a mercury-contact, a number of movable contact-pieces, a slide having a cam or groove, and a double solenoid having a movable core connected to said slide for operating the same, substantially as specified.

7. The combination of a variable-resistance shunt around a group of incandescent lamps with a mercury-contact, a number of movable contact-pieces, a slide having a cam or groove, a double solenoid having a movable core, and a dash-pot, substantially as specified.

8. The combination, with a variable-resistance shunt around a group of incandescent lamps, of a mercury-contact and a series of movable contact-pieces, N, consisting of wires lying in the same plane, each provided with

a projecting knee or fold, n, and a depending end, n', substantially as specified.

9. The combination, with a variable-resistance shunt around a group of incandescent lamps, of a mercury-contact, a number of movable contact-pieces, N, a slide, L, having a groove or cam, l³, a double solenoid having a sliding core, G', a dash-pot, and a friction-wheel, and a truck therefor, substantially as specified.

10. The combination, with a variable-resistance shunt around a group of incandescent lamps, of a mercury-contact vessel, K, provided with flanges or tracks l³, a number of movable contact-pieces, N, slide L, having groove l³, double solenoid G, having sliding core G', arm L', connecting said core and slide, friction-wheel l², and dash-pot M, substantially as specified.

11. The combination, with a variable-resistance shunt around a group of incandescent lamps, of a fixed contact, a series of movable contact-pieces leading to different parts of said resistance, a double solenoid having a movable core, and a slide having a cam or groove, substantially as specified.

12. The combination, with a variable-resistance shunt around a group of incandescent lamps, of a double solenoid having a movable core, a dash-pot, a slide having a cam or groove, and a number of movable contact-pieces operated thereby, substantially as specified.

13. The combination, with a variable-resistance shunt around a group of incandescent lamps, of a movable core of a solenoid, a grooved slide or cam, and a number of movable contact-pieces operated thereby, substantially as specified.

14. The combination of a variable-resistance shunt around a group of incandescent lamps with a number of movable contact-pieces, N, and a grooved slide, L, substantially as specified.

15. The combination, with a group of incandescent lamps in multiple arc, of a shunt around such group, having included therein a variable resistance, consisting of a carbon pile with metallic plates inserted at intervals, 115 said plates being connected with a series of contact-pieces, substantially as described.

16. The combination, with a group of incandescent lamps in multiple arc, of a shunt around such group, having included therein a series of carbon plates or blocks, c', and a series of contact-pieces connected with said series of carbon blocks at different points, substantially as specified.

17. The combination, with a group of incandescent lamps in multiple arc, of a shunt around such group, having included therein a series of carbon plates or blocks, c', and a series of contact-pieces, as N, connected with said series of blocks at different points, the blocks 130 in the first part of said series being of larger area than those in the latter part thereof, substantially as specified.

18. The combination, with a group of in-

candescent lamps in multiple arc, of a shunt around such group having a variable resistance included therein, a number of movable contact-pieces connected with different parts 5 of said resistance, a mercury-contact, a slide having a groove or cam, a double solenoid having a movable core for operating said slide, a relay having two movable armatures, two contact-pieces operated thereby, and two mercury-contacts, substantially as specified.

19. The combination, with a variable-resistance shunt around a group of incandescent lamps, of a solenoid and mechanism operated thereby for varying said resistance, and a relay having two movable switch-levers and mercury-contacts, substantially as specified.

20. The combination, with a variable-resistance shunt around a group of incandescent lamps in multiple arc, of a double solenoid 20 and mechanism operated thereby for varying said resistance, and a relay having two movable switch or armature levers and weighted lines for retracting said levers, substantially as specified.

21. The combination, with a variable-resistance shunt around a group of incandescent lamps in multiple arc, of a double solenoid and mechanism operated thereby for varying the resistance of said shunt, and a relay having 30 two armature-levers and carrying contact-points, weighted lines for retracting said levers, and two mercury-contacts, substantially as specified.

22. The combination, with a main circuit, of 35 a local or lamp circuit having a number of incandescent lamps therein in multiple arc, a variable-resistance shunt around said lamps, a double solenoid, the coils of which are normally short-circuited for varying the resistance of said shunt, a relay to open and close the short circuits around the coils of said solenoid, a short circuit for cutting out both the lamps and the shunt-resistance, and means for closing said short circuit in case the current 40 through the lamps and the relay increases a certain prescribed extent above its normal amount—as, for example, the extent due to the extinction of two or three lamps—without corresponding change being made in the resistance of the shunt, substantially as specified.

23. The electric lighting system consisting in a main circuit, as A, a lamp-circuit, as B, incandescent lamps in multiple arc, as b', a shunt-circuit, as C, a variable resistance therein, as c, an electro-motive device for varying the resistance of said shunt, a relay to set said electro-motive device in operation, a short circuit, as P', and means for closing the same in 55 case said resistance-varying device fails to act, substantially as specified.

24. The electric lighting system consisting in a main circuit, as A, a lamp-circuit, as B, incandescent lamps, as b', in multiple arc, a shunt, as C, having included therein a variable resistance, as c, a double solenoid, as E' F', short circuits, as E F, around the coils of 60

said solenoid, a relay, as D, having a coil, as D', included in a branch, as b, and having a second coil, as D'', included in a short circuit, 7c as P', and an electro-magnet, as O, for holding said short circuit P' open, substantially as specified.

25. The combination, with a variable-resistance shunt around a group of incandescent lamps, of a series of contact-pieces, N, leading to different parts of said resistance, a contact-piece, P, for opening and closing a short circuit, as P', and a slide, L, having a cam or groove, l', for operating said contact-pieces 80 N, and also a cam, as p, for operating said contact-piece P, said cam p being so located or arranged in relation to said cam l' that the short circuit P' will not be opened until the resistance of the shunt is reduced to its minimum, substantially as specified.

26. The combination, with a variable-resistance shunt around a group of incandescent lamps, of an electro-motive device for varying the resistance of said shunt, a short circuit, 90 P', and an electro-magnet for closing said short circuit in case said resistance-varying device fails to act, substantially as specified.

27. The combination, with a variable-resistance shunt around a group of incandescent lamps, of an electro-motive device for varying the resistance of said shunt, a short circuit, as P', and an electro-magnet to close said short circuit in case the resistance-varying mechanism fails to act, and to keep the same closed until 100 the resistance of the shunt is reduced to its minimum.

28. The combination, with a variable-resistance shunt around a group of incandescent lamps, of an electro-motive device for varying 105 the resistance of said shunt, a short circuit, as P', an electro-magnet, D, for closing the same, having a coil, D', in circuit with the lamps, and a second coil, D'', included in said short circuit P', substantially as specified.

29. The combination, with a variable-resistance shunt around a group of incandescent lamps, of a mercury-contact, a number of movable contact-pieces, N, a movable contact-piece, P, and a slide, L, provided with cams l' and p, substantially as specified.

30. The combination of a mercury-contact with movable contact-pieces N, movable contact-piece P, and an electro-magnet, as O, to hold said contact P out of the mercury, substantially as specified.

31. The combination of movable contact-piece P with electro-magnet O, having armature-lever o, provided with catch or shoulder o', electro-magnet D, and lever R, to release 125 said contact-piece P, substantially as specified.

32. The combination, with a double solenoid, of a relay-magnet, short circuits around the two coils of said solenoid, the movable core of said solenoid, and a dash-pot, substantially as specified.

33. The combination, with a variable resistance, a series of contact-pieces leading to different parts of said resistance, a double

solenoid having a movable core, a relay-magnet, short circuits around the two coils of said solenoid, a dash-pot, and mechanism for operating said contact-pieces, substantially as specified.

5 34. The combination, with an electro-magnet, of its movable armature, and a weighted line for retracting the same, said weight consisting of two extensible parts, whereby the same may be adjusted.

10 35. The combination, with a group of incandescent lamps in multiple arc, of a shunt around such group, having included therein a variable resistance having a greater number of parts or divisions than there are lamps in the group, substantially as specified.

15 36. The combination, with a group of incandescent lamps in multiple arc, of a variable-resistance shunt around said group, an elec-

tro-motive device for varying the resistance of 20 said shunt, and a short circuit, as P', in which said electro-motive device is included, for causing said electro-motive device to go through its work or motion and reduce the resistance of said shunt to its minimum when 25 the current is first turned on and before it reaches the lamps, and means for opening said short circuit after the resistance of said shunt-circuit is thus reduced to its minimum, so that in case the resistance-changing mechanism 30 should not happen to be in working order no injury can result to the lamps, substantially as specified.

HAROLD P. BROWN.
